(57) **CLAIM**

The ornamental design for an electronic cutting machine, as shown and described.

DESCRIPTION

FIG. 1 is a front/right side isometric view of the electronic cutting machine,

FIG. 2 is a rear/right side isometric view of the electronic cutting machine of FIG. 1,

FIG. 3 is a front elevational view of the electronic cutting machine of FIG. 1,

FIG. 4 is a rear elevational view of the electronic cutting machine of FIG. 1,

FIG. 5 is a right side elevational view of the electronic cutting machine of FIG. 1,

FIG. 6 is a left side elevational view of the electronic cutting machine of FIG. 1,

FIG. 7 is a top plan view of the electronic cutting machine of FIG. 1; and,

FIG. 8 is a bottom view of the electronic cutting machine of FIG. 1.

The shade lines in the Figures show contour and not surface ornamentation.

The broken lines in the Figures show portions of the electronic cutting machine which form no part of the claimed design.
